J. T. CALDWELL,
WASHBOARD HOLDER,
APPLICATION FILED APR. 5, 1917.

1,251,861.

Patented Jan. 1, 1918.

UNITED STATES PATENT OFFICE.

JOHN T. CALDWELL, OF MENAN, IDAHO.

WASHBOARD-HOLDER.

1,251,861.

Specification of Letters Patent.

Patented Jan. 1, 1918.

Application filed April 5, 1917. Serial No. 160,026.

To all whom it may concern:

Be it known that I, JOHN T. CALDWELL, a citizen of the United States, residing at Menan, in the county of Jefferson and State 5 of Idaho, have invented certain new and useful Improvements in Washboard-Holders; and I do hereby declare the following to be a full, clear, and exact description of the invention, such as will enable others 10 skilled in the art to which it appertains to make and use the same.

This invention relates to improvements in a wash board holder and has for one of its objects the provision of a device of this 15 character, which will secure the wash board to a tub and which will permit the wash board to be moved within the wash tub when desired and which will return the same to its normal position after being once 20 moved.

Another object of this invention is the provision of a coiled spring having each end connected to the wash board upon each side thereof and having means thereon for connecting the spring to the wash tub so that the wash board will be held to the tub and prevented from moving therein accidentally.

Another object of this invention is the provision of a hook, slidably mounted upon 30 the coiled spring and adapted to engage the tub for establishing a connection between the spring and tub to properly position or hold the wash board therein.

A still further object of this invention 35 is the provision of a wash board holder of the above stated character, which shall be simple, durable and efficient, and which may be manufactured and sold at a comparatively low cost.

With these and other objects in view as 40 will become more apparent as the description proceeds, the invention consists of certain novel features of construction, combination and arrangement of parts as will 45 be hereinafter more fully described and claimed.

For a complete understanding of my invention, reference is to be had to the following description and accompanying drawing, 50 in which:

Figure 1 is a fragmentary vertical sectional view of a wash tub having a wash board therein and connected thereto by a wash board holder constructed in accordance 55 with my invention,

Fig. 2 is a fragmentary elevational view partly in section of the same,

Fig. 3 is a longitudinal sectional view of a holder,

Fig. 4 is a transverse sectional view taken 60 on the line 4—4 of Fig. 3.

Referring in detail to the drawing, the numeral 1 indicates as an entirety, a wash board of the ordinary construction, consisting of the side members 2. A loop fastener 65 3 has thereon an eye-bolt 4, which is turned into one of the side members 2 adjacent the upper end of the wash board as clearly shown in Fig. 2.

The loop fastener 3 has its ends disposed 70 in opposite directions as shown at 5 and received within one end of a coiled spring 6. The portion of the coiled spring which receives the loop fastener 3 is surrounded by a cuff or collar 7 to prevent undue expanding 75 of the coiled spring at this point. The opposite end of the coiled spring has secured therein, a hook 8, which has one end bent as illustrated at 9 to engage the runs of the coiled spring, while its opposite end is disposed upon the exterior of the coiled spring and is adapted to receive an eye-bolt 10, which is turned into the other side member 2 from which the eye-bolt 4 is connected. A cuff or collar 11 surrounds the coiled 80 spring and the free end of the hook 8 to prevent the eye-bolt 10 from accidentally becoming detached therefrom, and also providing means whereby the eye-bolt 10 may be detached from the hook 8 when desired 85 by sliding the cuff or collar 11 from engagement with the free end of the hook 8.

An attaching member 12 is slidably mounted 90 upon the coiled spring 6 and has pivotally secured thereto, a hook 13. The hook 13 is 95 adapted to be hooked under the supporting flange 14 of a wash tub 15, whereby the spring is connected to the wash tub and which will hold the wash board 1 within the wash tub.

From the foregoing description taken in connection with the accompanying drawing, it will be noted that a holder has been provided, which may be readily applied to an ordinary wash board and which can be connected to the wash tub for the purpose of holding the wash board within the tub in an operative position and which will permit the wash board to be moved within the tub so as to easily and readily remove clothing and 110

other articles, which may be within the tub and under the board. When the device is in use as shown in Fig. 1, the tension of the spring is only sufficient to hold the wash board in engagement with the tub and will not be of sufficient strength to move or swing the legs of the wash board from engagement with the bottom of the tub. It will also be noted that a device of this character being 10 partially constructed from a coiled spring will obviate the necessity of a person bearing or resting upon the wash board 1 while using the same to hold it downwardly within the wash tub and which will permit a person to 15 be free to move and occupy any position that they may desire as the spring normally holds the wash board in operative position.

While I have shown and described the preferred embodiment of my invention, it 20 will be understood that minor changes in construction, combination and arrangement of parts may be made without departing from the spirit and scope of the invention as claimed.

25 Having thus described my invention, what I claim is:

1. A wash board holder comprising an elastic member, means for connecting the ends of the member to the sides of a wash 30 board, and means for connecting the member to the wash tub to hold the wash board within the wash tub and which will permit movement of the wash board in relation to the wash tub.

Copies of this patent may be obtained for five cents each, by addressing the "Commissioner of Patents. Washington, D. C."

2. A wash board holder comprising a 35 coiled spring, means for securing the ends of the coiled spring to a wash board, and means for detachably connecting the spring to a wash tub for holding the wash board within said tub and which will permit the 40 wash board to be moved with relation to the wash tub.

3. A wash board holder comprising a coiled spring, an eye-bolt pivotally connected to one end of the coiled spring and secured to one side of a wash board, an eye-bolt removably secured to the other end of the coiled spring and secured to the opposite side of the wash board, and means carried by the coiled spring for engagement with the 50 wash tub to cause the coiled spring to hold the wash board in the wash tub and permit it to move with relation to the wash tub.

4. A wash board holder comprising a coiled spring, means for detachably connecting the coiled spring to a wash board, and a hook slidably mounted upon the coiled spring and adapted to engage a wash tub to cause said spring to hold the wash board within the wash tub and which will permit the wash board to be moved with relation to the wash tub.

In testimony whereof I affix my signature in presence of two witnesses.

JOHN T. CALDWELL.

Witnesses:

CARL R. PETERSON,
JOHN H. YEARSLEY.
